UNITED STATES PATENT OFFICE.

JOSEPH P. SANDER, OF SPOKANE, WASHINGTON.

MAIL CATCHING AND DELIVERING MECHANISM.

1,167,936.

Specification of Letters Patent. Patented Jan. 11, 1916.

Application filed September 2, 1914. Serial No. 859,866.

To all whom it may concern:

Be it known that I, JOSEPH P. SANDER, a citizen of the United States, residing at Spokane, in the county of Spokane and State of Washington, have invented certain new and useful Improvements in Mail Catching and Delivering Mechanism, of which the following is a specification.

This invention relates to improvements in mail catching and delivery mechanism for use in transferring mail bags from a car to a station, and vice versa.

One of the most important objects of the invention is to provide a catching device which is adapted to grasp the body of the mail bag so as to prevent lashing and whirling of the bag at the moment of catching impact.

A further object relates to the construction of the bag grasping catching means wherein the same is incorporated in the form of a basket portion for receiving the bag, and a retaining portion adapted to be swung against the caught bag by impact of the bag with the catching portion so as to firmly grasp the bag against any displacement thereof while the same is being swung into the car.

A further object of the invention consists in an improved mounting for the catching means to permit the latter to swing about a fixed axis under the thrust of catching impact, said mounting means functioning to offer an increasing resistance to such swinging impact movement thereby neutralizing the shock which usually results when a caught bag is abruptly arrested.

Further objects and features of the invention will be more fully described in connection with the accompanying drawings and will be more particularly pointed out in and by the appended claims.

In the drawings: Figure 1 is a view in side elevation of a portion of a car and a station and indicating the position which the parts will assume when bags are about to be transferred from the car to the station and vice versa; Fig. 2 shows the position of the mechanism after transfer of the bags has been effected; Fig. 3 is a plan view showing the parts in the position which they assume and are shown in Fig. 1; Fig. 4 is a view in elevation of a mounting shaft structure for the catching device; Fig. 5 is a perspective view of the catching device detached from its mounting shaft; Fig. 6 is a

plan view showing the catching device in the position which it assumes before the bag is caught; Fig. 7 is a plan view showing the position after the bag is caught; Fig. 8 is a detailed view looking in the direction of arrow 8 of Fig. 6; Fig. 9 is an end view of a socketed arm holder; Fig. 10 is a plan view of one of the catching arms; Fig. 11 is an edge view thereof; and Fig. 12 is an edge view similar to Fig. 11 with the bag transferring devices in a different position.

Like characters of reference designate similar parts throughout the different figures of the drawings.

As illustrated, 1 designates the car of a train which is indicated as running in the direction of the arrow, and 2 designates the station.

I will first describe the car mechanism 75 of my invention, which as shown, includes a shaft 3 on which the catching device of the car is mounted. The shaft 3 is provided on its lower end with a threaded journal 4 which has a bearing in a threaded step 80 base 5, the latter being adapted to be mounted on the floor of the car. Said shaft 3 is also provided with a spring abutment 6, and its remaining end is journaled in a bearing 7, mounted on the car. Interposed between 85 the abutment 6 and the bearing 7 is a spring 8, the function of which is to frictionally resist rotated movement of the shaft 3 under impact thrust, the threaded connection at 4 and 5 being of sufficient pitch to axially 90 shift the shaft in a manner to compress spring 8. This threaded connection increases axial shifting movement of the shaft as the latter rotates so that the spring offers an increasing resistance as the bag is re- 95 tracted under impact and swings into the car thereby neutralizing the shock of final movement.

The abutment 6 may be, and in the present construction constitutes the hub 9 of a 100 socketed catching arm holder 10. The hub 9 is fixed on the shaft 3 by a set screw 11 which not only affords adjustment in correctly positioning the holder in its arm, but also to vary the tension of spring 8. The 105 arm holder 10, as will be seen more clearly by reference to Fig. 9, is provided with a socket 12 shaped to correspond to the cross section of a catching arm 13. The catching arm 13 is longitudinally and oppositely 110 feathered or ribbed, as indicated at 14, the socket 12 having correspondingly shaped off-

sets 15 for receiving said ribs in a manner to secure firm anchorage of the arm. The arm 13 is bored at 16 and may be fixed in the holder by a headed pin 17 which is simply dropped through a bore in the holder and into bore 16. The outer end of arm 13 is provided with a catching fork comprising forked portions 18 having diverging terminals 19. The crotch 20 of the fork is somewhat enlarged with respect to the throat 21 and from the entrance of the throat extending toward the crotch 20, I provide pairs of retainers in the form of lugs 22, the ends 23 of which form shoulders normally resisting movement of a transfer line or device out of the fork after the bag has been caught. The lugs 22 are disposed on opposite sides of the fork for interchangeable use of the latter in traveling in either direction. The transfer line of the bag may be in the form of a shank or chain 24 having a ball or head 25 which is adapted to ride upon the forked ends and lugs 23 as the shank passes therebetween. After the ball or head 25 has descended behind the shoulders 23, the latter will resist any outward movement of the head. This outer end of the arm 13, is also provided with a delivery fork 26. The terminal ends 26 are enlarged, as shown in Figs. 11 and 12, so that when a transfer device 28, of a bag to be delivered, is disposed in position in said fork, it will be retained therein against any tendency of air resistance to detach it.

It is one of the primary objects of this invention to prevent the whirling and lashing which usually results immediately following the impact of a caught bag, and to avoid this troublesome defect, my invention provides for grasping the bag about the body thereof in such a manner that strain will not only be taken off from the bag suspension means but so as to avoid any possibility of injury to operatives in the car. Referring to this feature of my invention more specifically, the said means includes a basket-like structure comprising a basket portion 29 and a retaining portion 30. The basket portion comprises horizontal steel or like straps 31 which are curved, as indicated at 32 to receive the body of the bag, the free ends being attached to a stiffening bar 33 to rigidify the structure. The straps 31 are also connected near their opposite ends by a bar 34 and the terminal ends are bent to form rectangular loops 35 with the extreme terminals 36 riveted or likewise secured to the bar 34 and the ends 31. The loops 35 serve for mounting the basket structure upon the shaft 3, the latter being provided with hooks 37 on which the loops 35 are adapted to rest. The hooks 37 are hubbed at 38 and are adjustably anchored to the shaft by set screws 39.

Again referring to the specific construc-

tion of the basket means, 40 designates a shaft which is journaled in bearings 41, of the straps 31. Between the ends of said shaft 40, I mount the retainer 30, which as will be seen more clearly by reference to Fig. 8, is provided with lugs 42 which are spaced apart from each other to journal on said shaft 40. Between said lugs 42, and fixed on said shaft 40, is a ratchet wheel 43. A pawl 44 engages the ratchet wheel 43 and is pivotally mounted at 45, the free end of said pawl being acted upon by a spring 46 to normally hold the ratchet end of the pawl against the teeth of the ratchet wheel 43. The retainer 30 is provided with an impact arm 47, formed by extending the retainer 30 beyond the shaft 40, the impact arm 47 presenting a convex surface in the path of the bag while the straps 32 present a concave surface or face to the bag.

When the parts are in the position shown in Fig. 6, the basket means is ready to receive a bag. As the bag enters the basket means it will first strike the impact arm and swing the latter from the position shown in Fig. 6 to the position shown in Fig. 7. This serves to rotate the retainer 30 about the shaft 40 into following relation to the bag, so that the latter which is indicated at A, will be embraced by the basket means. As the retainer swings about shaft 40 the pawl 44 rides idly over the ratchet 43 and when the retainer reaches a final position, it will be held in such position by pawl 44. In Fig. 7, I have shown the parts so proportioned that they will loosely embrace the caught bag A, but it will be understood that by changing the proportions, I may cause the retainer to firmly engage and co-act with the basket portion, through the interposed bags, to firmly grasp and hold the same in place.

When a bag is to be delivered from the car device to the station, the transfer line or head 28 is disposed in the forked end 26, of arm 13, as indicated in Fig. 3, the bag being designated at B. The basket catching device is opened out ready to receive a bag C, held by station device X. This station device does not constitute a feature of the present invention and will therefore not be specifically described as its function can be performed by any preferred type of means that will hold a bag in position to be caught by the device of my invention.

My improved station device consists in providing shafts 48 and 49 mounted in upper and lower bearings 50-51 and 52 and 53. Each shaft is provided with upper and lower catching arms which are forked as indicated in Fig. 3, the upper arms being indicated at 54 and 55, and the lower arms at 56 and 57. The bearings 51 and 53 are threaded bearings which function to shift the shafts axially for the same purpose as

has been described in connection with Fig. 4. I also equip the shafts with springs 58 and 59 which likewise function in a manner similar to spring 8.

5 The transfer devices 28 of bag B will be caught by the forks of arms 54 and 56 before the catching device of basket reaches bag C. The impact of bag B will swing the forked arms 54 and 56 and the shaft 48 10 to the left of Fig. 1, as shown in Fig. 2. Subsequently, the basket means will reach bag C and grasp the same in the manner hereinbefore described, the catching fork of arm 13 also engaging the transfer chain or 15 line of bag C.

It will be understood that arms 55 and 57 are employed for catching bags from trains running in a direction opposite to the direction indicated by the arrow in Fig. 1.

20 It is believed that the advantages and utility of my invention will be fully understood from the foregoing description, and while I have herein shown and described one specific form of my invention, I do not 25 wish to be limited thereto except for such limitations as the claims may import.

I claim:

1. In a mail catching device, a rotatable shaft provided with a spring abutment and a threaded journal, a threaded bearing engaging said journal for shifting said shaft 30 axially during impact rotation thereof, a second bearing of the shaft, and a coiled spring interposed between said abutment

and said second bearing for compression by 35 said shaft to resist impact rotation of the latter, said shaft having bag catching means thereon, substantially as described.

2. In a mail catching device, a catching mechanism, a shaft for supporting said 40 mechanism, and bearing means for causing axial shifting movement of said shaft during impact rotation thereof, and a spring means acted upon by such axial shifting movement of said shaft to resist impact rotation of the 45 latter, substantially as described.

3. In a mail pouch transferring mechanism for pouches having endwise projecting pins or shanks provided with enlarged heads, a catching device including a horizontally 50 disposed fork having a crotch enlarged with respect to the throat of said fork but of reduced size with respect to said head, the forked portions of said fork having retaining lugs extending along the throat and inclined upwardly toward and terminating in abrupt shoulders adjacent the juncture of said throat and crotch for movement of said head upwardly along said lugs and downwardly behind said shoulders into said enlarged crotch to be supported in the latter, 55 substantially as described.

In testimony whereof I affix my signature in presence of two witnesses.

JOSEPH P. SANDER.
